UNITED STATES PATENT OFFICE.

HOLLIS C. CONRAD, OF BEAVER FALLS, PENNSYLVANIA.

AMUSEMENT HOUSE.

Application filed February 5, 1924. Serial No. 690,762.

The invention relates to amusement houses of illusion type, wherein the floor of the house is at an angle to the horizontal, and preferably no part of the floor in a horizontal plane, and has for its object to provide in combination with an amusement house of this character means whereby persons entering the house and passing through the same, will have to take a circuitous course, thereby passing over various inclinations of the floor, and increasing the illusion.

A further object is to provide means whereby the illusion within the house is further increased by flowing water, apparently flowing up hill at an upwardly inclined angle in relation to the floor of the house.

A further object is to provide seats within the house adapted to be used by persons passing through the house, and from which seats, on account of the illusion created on the minds of persons passing through the house, persons experience considerable difficulty in rising from the seats.

A further object is to provide adjacent entrance and exit from the house, and a circuitous passage through the house from the entrance to the exit.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a side elevation of the amusement house, showing the outer vertical wall thereof, broken away to better illustrate the structure.

Figure 2 is a horizontal sectional view taken on line 2—2 of Figure 1.

Figure 3 is a vertical transverse sectional view taken on line 3—3 of Figure 1.

Referring to the drawing, the numeral 1 designates the outer walls of the amusement house, which walls are preferably vertically disposed as shown to simulate a conventional form of house to persons approaching the amusement house. Disposed within the walls 1 is the illusion house 2, which house has its floor 3 in a plane other than horizontal, and preferably with its corner 4 at a zero elevation, its corner 5 at a three foot

elevation, its corner 6 at a four foot elevation and its corner 7 at a seven foot elevation, consequently the floor 3 is disposed at an angle which will confuse a person passing through the amusement house, and in combination with the inclined walls 9 of the amusement house 2, which walls are preferably at a right angle to the floor 3, will create an illusion which will baffle and confuse a person passing through the amusement house. It has been found that by providing a circuitous passage through the amusement house, whereby a person passing therethrough will be compelled to move over the floor at various angles, that the illusion is further intensified and persons further baffled. To obtain this result railings 10 and 11 are provided, which rails form a continuous circuitous passage 12 from the entrance 13 of the amusement house to the exit 14 of the amusement house. The circuitous passage extends from the entrance 13 towards the ends of the illusion house 2, and thence to the other end of the illusion house, and back to the exit 14, which exit is adjacent the entrance 13. It will be seen that when a person passes through the amusement house, through the circuitous passage 12, that during said passage they will move transversely over the floor, going up an incline, then longitudinally down an incline and transversely down an incline until the end 9^a of the house is reached, after which when the person starts towards the end 9^b of the illusion house, the longitudinal portions 15 of the circuitous passage 12 are upwardly inclined, which is the reverse situation to the other side of the passage. The reversing of the incline incident to the circuitous passage further confuses or muddles the person passing through the amusement house, and it has been found that the illusion is so intensified that it is with extreme difficulty that many persons make the entire passage through the amusement house. Disposed within the illusion house 2, preferably adjacent the ends thereof are seats 16, on which persons passing through the circuitous passage will seat themselves on account of the illusion and confusion, however it has been found that on account of the illusion and confusion of the mind that persons after sitting on the seats are so confused that they can not regain their equilibrium without considerable difficulty, and consequently have a great deal of difficulty in rising from the seats.

To further increase the illusion, a water trough 17 is provided adjacent one side of the illusion house 2, where it can be easily observed by persons passing through the house. The trough 17 preferably extends from the high corner 7 of the floor 3 and inclines downwardly towards the corner 5 at a considerably less angle than the inclination of the floor, and consequently the discharge end 18 of the trough is spaced a substantial distance from the floor, and the intake end 19 relatively close to the floor, consequently when water is flowing through the trough from the water supply spigot 20, the illusion, incident to the inclination of the floor 3, and the illusion house 2, creates the impression that water is flowing up hill, thereby further confusing persons passing through the circuitous passage. Although the water trough 17 is described as disposed adjacent one side of the amusement house, it is obvious that it may be placed in any position desired when creating the illusion of water running up hill.

From the above it will be seen that a circuitous passage is provided in combination with an amusement house, through which a person will be compelled to pass over the inclined floor at various angles in passing through the house from the entrance to the exit thereof, thereby further increasing the illusion by confusing the mind, that means is provided for additionally increasing the illusion and confusion of the mind, which means comprises water apparently running up hill, and seats are provided within the amusement house for the use of persons passing through the house, and from which seats persons experience difficulty in rising.

The invention having been set forth what is claimed as new and useful is:—

1. The combination with an amusement house having an inclined floor, of seats disposed on said floor, parallel thereto and facing in the direction of the inclination thereof and a circuitous passage through the house formed by hand rails in parallel relation to the floor within the reach of a person passing through the circuitous passage, or while seated on the seats. 45
2. The combination with an amusement house having a diagonally inclined floor, adjacent entrance and exit, of a circuitous passage through said building continuously from the entrance to the exit, said circuitous passage covering the entire floor. 55
3. The combination with an amusement house having a diagonally inclined floor, an entrance, an exit, of a circuitous passage through said building continuously from the entrance to the exit, said circuitous passage covering the entire floor. 60
4. The combination with an amusement house having a diagonally inclined floor, an entrance, an exit, of a circuitous passage through said building continuously from the entrance to the exit, said circuitous passage traversing substantially the entire floor. 65
5. The combination with an amusement house having a diagonally inclined floor, adjacent entrance and exit, of a circuitous passage through said building continuously from the entrance to the exit, said circuitous passage traversing substantially the entire floor. 70

In testimony whereof I hereunto affix my signature.

HOLLIS C. CONRAD.
